(57) **CLAIM**

The ornamental design for a distributor, as shown and described.

DESCRIPTION

FIG. 1 is a front view of the ornamental design for a distributor;

FIG. 2 is a left side view thereof;

FIG. 3 is a right side view thereof;

FIG. 4 is a rear view thereof;

FIG. 5 is a top view thereof;

FIG. 6 is a bottom view thereof;

FIG. 7 is an upper, front isometric view thereof;

FIG. 8 is an upper, rear isometric view thereof; and,

FIG. 9 is a lower, front isometric view thereof.

The broken lines are included for the purpose of illustrating the portions of the distributor that form no part of the claimed design.
